DESIGN FOR A COAT

Morris Metzger, New York, N. Y.

Application September 11, 1936, Serial No. 64,804

Term of patent 3½ years

To all whom it may concern:

Be it known that I, Morris Metzger, a citizen of the United States of America, residing in city of New York, county of New York, and State of New York, have invented a new, original, and ornamental Design for a Coat, of which the following is a specification, reference being had to the accompanying drawing, forming part thereof.

I claim:

The ornamental design for a coat substantially as shown.

MORRIS METZGER.
